UNITED STATES PATENT OFFICE.

HAROLD COLBY, OF SPOKANE, WASHINGTON.

MOP-WRINGER.

No. 856,225.

Specification of Letters Patent.

Patented June 11, 1907.

Application filed June 7, 1906. Serial No. 320,816.

To all whom it may concern:

Be it known that I, HAROLD COLBY, a citizen of the United States, residing at Spokane, in the county of Spokane, State of Washington, have invented certain new and useful Improvements in Mop-Wringers; and I do hereby declare the following to be a full, clear, and exact description of the invention, such as will enable others skilled in the art to which it appertains to make and use the same.

This invention relates to the art of scrubbing, and consists more especially in an improved wringer for mops or clothes whose details of construction are set forth below, and which is illustrated in the accompanying drawings, wherein—

Figure 1 is a perspective view of this entire machine, ready for use as a mop wringer. Fig. 2 is a central vertical section showing the device in use and illustrating how a tub may rest upon the base. The second view illustrates how a spring or springs could be coiled on the rod which supports the bail, while the first view illustrates contractile springs as connecting the lower ends of the main levers.

Referring to the drawings, the numeral 1 designates a base, here shown as flat so that a tub may rest thereon as seen in Fig. 2; and from the sides of this base rise two uprights 2, while to the rear extend two side supports 3 which are connected at their outer extremities by a transverse rod 4. Pivoted in the upper ends of the uprights are two pairs of main levers 5, each preferably bent at an obtuse angle near its upper end as at 6, and each preferably pivoted to the upright at a point 7 within this bend. The two levers of each pair occupy reverse positions so that their short upper arms lie close together and nearly parallel when the long arms are forced apart as shown in Fig. 2.

Power is applied through a foot-lever 10 which preferably comprises the transverse member of a U-shaped bail 11 whose side arms extend from the foot-lever backward in parallelism over the base and are sufficiently spaced from each other to span a tub of ordinary size. At their rear ends they are pivoted as at 12 upon the rod 4, and if desired a spring or springs 30 (see Fig. 2) may be coiled on this rod and exert a tendency to normally raise the foot-lever.

13 designate two toggles one at each side of the machine, whose outer ends 14 are

pivoted to the lower ends of the main levers 5, and whose inner ends are pivoted to each other and to the side arms of the bail as at 15. In Fig. 1 I have shown two contractile springs 31 connecting the points 14 and standing outside the main levers 5 and within the uprights. These springs may be used instead of the single spring 30, and if they are employed their tendency is to draw the lower ends of the main levers together and raise the foot-lever as explained below.

20 designate two rollers which may be of rubber, wood, or other suitable material, and these are fast upon spindles 21 which are journaled in the upper ends of the main levers. The said rolls 20 are cylindrical rolls whose outer surfaces are concaved to the extent of one-sixteenth part of an inch, thus making the diameter of said rolls in 75 the center or at a point equi-distant from the ends one-eighth part of an inch less than at their ends. Said concave surface makes an arc or chord of a circle extending from the ends of said rolls inward, and concaving 80 toward the center of the rolls and thence out to the said ends. One of the spindles may be continued into a crank handle 22 if desired. 23 are gears which may also be mounted on these spindles if desired, and 85 they are of such size and shape that they will intermesh when the faces of the rollers all but touch each other. The parts are of desired proportions and materials, and if preferred the springs may be entirely omitted. 90

When this device is in use as a mop wringer, the tub usually sits upon the base within the bail. As the operator lifts the mop-head out of the tub he raises it (still dripping) and lets it down between the rollers, and then by applying pressure to the foot-lever the toggles cause the main levers to swing and the rollers to be approximated so as to squeeze the mop-head between them. If sufficient wringing is not accomplished by 100 forcibly withdrawing the mop-head, the crank-handle may be used to supplement this operation. When this device is used as a wringer for clothes, the bail is depressed further than when used as a mop wringer, so 105 that its foot-lever rests upon the floor or the base as seen in Fig. 2, and will retain this position where it will not interfere with the insertion or removal of the tub, above which latter the rollers stand and are operated in 110 the usual way. If the spring 30 is employed, the removal of the foot allows the bail to rise

and the rollers to open at any time; if the springs 31 are employed, it is possible to depress the foot-lever until the toggles are straight or their central pivots have passed 5 a straight line between their end pivots, when the springs 31 will hold the foot-lever depressed; and if no springs are employed, it will be necessary to lift the foot-lever before inserting the article to be wrung out.

- 10 It is possible to use this device in the ordinary operation of washing clothes and the like. When so employed, the tub containing the wet pieces of wash is placed on the base, and said pieces are successively raised 15 by hand or with the laundry stick and inserted between the rollers, the pressure is then applied by the foot-lever, and by turning the crank the clothes are wrung out and forced up where they can be passed on to the next 20 operation—the water wrung out meanwhile running back into the tub.

What is claimed as new is:

The herein described wringer, the same comprising a base having spaced uprights, 25 duplicate pairs of main levers of which each

lever is bent at an obtuse angle and pivoted at its bend to one of said uprights, two rollers connecting the upper ends of the levers, gears on the ends of said rollers a crank handle on the shaft of one roller, toggle levers 30 connecting the lower ends of the levers of each pair, contractile springs drawing said lower ends normally toward each other; rigid supports projecting to the rear from said uprights, a transverse rod connecting 35 the outer ends of said supports, and a U-shaped bail whose ends are pivoted on said rod, whose sides are pivoted to the central pivots of said toggles and whose transverse central piece forms a foot-lever, the position 40 of said rod being such that when said foot-lever is completely depressed the central pivots of the toggles are below a line through their end pivots, for the purpose set forth.

In testimony whereof I hereby affix my 45 signature in presence of two witnesses.

HAROLD COLBY.
